Primary Examiner—Theodore M. Shooman
Attorney, Agent, or Firm—Terry M. Gernstein**[57] CLAIM**

The ornamental design for a wrist supported remote control, as shown and described.

DESCRIPTION

FIG. 1 is a perspective view of the wrist supported remote control embodying the design of the present invention;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom view thereof.

FIG. 1

FIG. 2

FIG. 3

FIG. 4

FIG. 5

FIG. 6
